UNITED STATES PATENT OFFICE.

GEORGE N. MAS, OF LYNCHBURG, VIRGINIA.

DESIGN FOR A BOTTLE.

Application filed June 29, 1923. Serial No. 6,613. Term of patent 14 years.

To all whom it may concern:

Be it known that I, GEORGE N. MAS, a citizen of the United States, and a resident of the city of Lynchburg, county of Campbell, in the State of Virginia, have invented a certain new, original, and ornamental Design for a Bottle, of which the following is a specification, reference being made to the accompanying drawing, forming part thereof.

In the drawing the single figure shows an elevation of a bottle embodying my design,

I claim—

The ornamental design for a bottle as shown.

In testimony whereof I have signed my name to this specification in the presence of two subscribing witnesses.

GEORGE N. MAS.

Witnesses:
